[57] CLAIM

The ornamental design for a combined spout and handle set, as shown and described.

DESCRIPTION

FIG. 1 is a top perspective view of a combined spout and handle set showing my new design;

FIG. 2 is a front elevational view thereof;

FIG. 3 is a top plan view thereof;

FIG. 4 is a right side elevational view thereof, the left side being a mirror image of the right side shown;

FIG. 5 is a rear elevational view thereof;

FIG. 6 is a bottom plan view;

FIG. 7 is a top perspective view of a modified form of the combined spout and handle set shown in FIG. 1;

FIG. 8 is a front elevational view of FIG. 7;

FIG. 9 is a top plan view of FIG. 7;

FIG. 10 is a left side elevational view of FIG. 7, the right side being a mirror image of the left side shown;

FIG. 11 is a rear elevational view of FIG. 7; and

FIG. 12 is a bottom plan view of FIG. 7.
